UNITED STATES PATENT OFFICE.

FRED EVANS, OF SUMMIT, NEW JERSEY, ASSIGNOR TO ERIC T. TRANZEN, OF MAPLEWOOD, NEW JERSEY, AND ARTHUR C. HENSLER, OF NEWARK, NEW JERSEY.

ADJUSTABLE STRIKER PLATE FOR DOORS.

Application filed November 18, 1920. Serial No. 423,776.

To all whom it may concern:

Be it known that I, FRED EVANS, a citizen of the United States, residing in Summit, in the county of Union and State of New Jersey, have invented certain new and useful Improvements in Adjustable Striker Plates for Doors, of which the following is a specification.

This invention relates to that class of devices used in holding the free edge of a swing door with respect to its jamb and particularly to doors provided with bevel ended, spring extended bolts, retractable by manually operable means extending from the side 15 of the door.

Keepers for such door bolts are usually fixed rigidly upon the jamb, with no provision for wear, distortion of the door or its jamb, and with no means whereby the door may be held securely when ajar, a condition frequently desirable, as in obtaining air or light.

The object of this invention is to provide a keeper capable of securing the door 25 when partially closed and also to hold the door in close relation to its jamb, preventing vibration, noise or the passage of a draught of air, irrespective of wear or perversion of parts.

This and other objects such as convenience in adjustment, neatness in appearance and range of utility, are attained by the novel construction and arrangement of parts hereinafter described and shown in the accompanying drawings, forming a material part of this specification, and in which:—

Figure 1 is a perspective view showing the preferred embodiment of the invention.

Figure 2 is a plan view of the same.

Figure 3 is an end elevation thereof.

Figure 4 is a central section view of the keeper showing its application.

Figure 5 is a perspective view looking at the lower side of a modified form of keeper.

Figure 6 is a plan view of the same.

Figure 7 is a sectional view taken on line 7—7 of Fig. 6.

Figure 8 is a view similar to Fig. 5, but showing another modification.

Figure 9 is a plan view of the same.

Figure 10 is a sectional view taken on line 10—10 of Fig. 9.

In the preferred embodiment of the invention, as shown in Figs. 1 to 4, and par-

ticularly the latter figure, the device is shown as assembled with the side 15, and hinged door 16 of a closed vehicle, the door having a plate 17 overlying the diagonal joint 18 between its edge and the jamb. 60

Set in the door is a spring actuated lock 19, its bolt 20 being normally extended but retractable by proper manipulation of the extending handle 21 as is usual with devices of this character. 65

The front edge of the door jamb contains a transverse recess 22 into the bottom portion 23 of which the spring bolt 20 enters to engage with the keeper.

This keeper comprises a substantially rectangular body 25 having lateral plate projections 26 at the front provided with countersunk openings 27 for the reception of screws which also pass through annular bosses 28 on the bottom of the plates acting 75 as dowels, whereby the keeper is held securely in operative position.

A keeper catch 30, integral with the body, has its diagonally curved surface 31 extending from a point in the plane of the 80 lateral projection rearwardly over the body, the same being adapted to receive the thrust of the curved portion of the spring bolt 20 presented to it in closing the door 16, the bolt being thus pressed back until it has 85 passed the highest part of the catch and engaged the surface 32, holding the door slightly ajar.

The rear portion of the body 25 contains a rectangular opening 33 particularly extending under the back of the catch 30, as at 90 34, and resting on the body 25 is a movable catch 35, its diagonally curved outer face 36 being similar to but rearward of the fixed catch 30. 95

Formed with the lower side of the catch 35 is a lug 37 extending through the opening 33 being guided therein and provided with a transverse cut 38 for a reason further apparent.

An adjusting screw 40 having a head 41 set in a recess 42 formed centrally at the extreme front of the body and an end 43 revolubly engaged in the rear wall of the base, passes longitudinally through the lug 37 so as to impart motion to the catch 35 when the screw is turned, thus adjusting the movable catch relative to the fixed catch and obviously, also with the spring bolt 20. 105

It is to be noted that the movable catch 110

overhangs the body 25 at the rear and is equivalent in surface dimensions with the fixed catch.

- When the movable catch has been adjusted 5 to hold the door tightly closed it is held either by the spring effect of the bifurcated lug 37 on the screw or by permitting its lower surface to contact with the bottom of the recess 22.
- 10 In the modification shown in Figs. 5, 6 and 7 the body 50 and fixed front catch 51 are integrally formed and provided with flat lateral extensions 52 having dowel bosses 53 containing screw openings 54.

- 15 Formed centrally in the bottom of the body is a longitudinal groove 55 receptive of a tongue 56 formed with the movable catch 57, the same being extended laterally as shown to agree in width with the fixed 20 catch 51.

On the upper surface of the tongue 56 are a plurality of serrations or teeth 58, corresponding teeth 59 being formed on the contacting portion of the wall surface of the 25 groove 55, these teeth co-operating to hold the movable catch in adjustment which is obtained by slackening the screws passing through the openings 54 and sliding the movable catch and tongue as may be desired, 30 then tightening the screws to clamp the keeper in place.

A similar device is shown in Figs. 8, 9 and 10, the only difference being that the teeth 58 and 59 are omitted and in place thereof the tongue 56 is allowed to slide freely in the 35 groove 55, teeth 60 being formed on the bottom of the tongue adapted to engage directly with the material of the door jamb when urged by the attaching screws.

40 From the foregoing it will be seen that a neat and convenient form of keepers have been disclosed each of which may be used to maintain a door in a partially closed position or to hold the same in tight engagement, 45 the movable catch being readily adjusted to compensate for wear or malformation of parts should they occur.

It will also be obvious that minor modifications can be made not necessitating inven-

tion and which are included in the general scope of the invention as herein disclosed and set forth in the appended claims.

I claim—

1. A spring bolt keeper comprising a body member having laterally extending attaching means and containing an open recess in its rear portion, a catch formed integrally at the front of said body, a second catch movable on said body, a bifurcated lug on said movable catch extending into said recess and a screw journaled in said body engaging the bifurcated portion of said lug whereby said second catch may be adjusted. 51

2. A bolt keeper comprising a body having a recessed base, a catch extending from said body at the front thereof, a second catch arranged in tandem slidably on the body, a base formed with said second catch engaged in the recess of said body base, means for adjusting the movable catch and means 60 on the base of said movable catch whereby it is held in adjustment. 65

3. A bolt keeper comprising a body member having laterally extending attaching means and containing an open recess in its 70 rear portion, a catch formed integrally at the front of said body, a second catch movable on said body provided with means extending into said recess and means carried by said body engaging the said means extending into 75 the recess whereby said second catch may be adjusted. 80

4. A bolt keeper comprising a body having a recessed base and laterally extending attaching means, a catch extending from said body at the front thereof, a second catch arranged in tandem slidably on the said body, an extension formed with said second catch engaged in the recess of said body base, and means integrally formed on one of said 85 90 catches whereby it is held in adjustment.

This specification signed and witnessed this 10th day of November, 1920.

FRED EVANS.
